UNITED STATES PATENT OFFICE.

CHARLES E. HOPKINS, OF PLAINFIELD, NEW JERSEY; THE PLAINFIELD TRUST COMPANY ADMINISTRATOR OF SAID CHARLES E. HOPKINS, DECEASED.

STEREOTYPE APPARATUS.

Application filed May 17, 1922, Serial No. 561,663. Renewed July 2, 1925.

To all whom it may concern:

Be it known that I, CHARLES E. HOPKINS, a citizen of the United States, residing at Plainfield, in the county of Union and State of New Jersey, have invented a new and useful Stereotype Apparatus, of which the following is a specification.

This invention is intended for use on a casting apparatus for the production of curved stereotype printing plates for use on high speed printing press cylinders, the die face of the cast being formed by a flexible matrix. I have shown it in a form comprising a concave back fixed between side frames in a vertical position. Each side frame has a track over which rollers carry a co-acting convex core, means are provided for turning the core from a horizontal position in front of the back's concavity to a vertical position within the said concavity. The principal features of this invention are:

The arrangement of a pouring sheet on rock arms to cooperate with the rock motion of a core and pivot out of the back on to a support above and away from its concavity.

The arrangement of a bottom ring having a concave face for forming a bevel on the lock up edge of a cast, and an opposing bevel for forming a rib side on said cast, for the purpose of locating the joining of the core and ring at the face of said rib.

The locating of ledges on the back and bottom ring to grip the bolster of a matrix so it is bent or crimped.

The arrangement of matrix positioning fingers so they are moved into and out of position automatically.

The arrangement of plate rail guides to hold and carry the rail past the straight edges of a core, in alignment and parallel with the core, and thereafter move the said rails in the reverse direction.

The joining of a pair of casting bars through the outer ends of a pair of toggle arms, and the joining of the pivot pins of the toggles to a slide bar, and the attaching of a lever to one of the toggle arms, through which the toggles can be expanded to move the casting bars away from each other, and move back by reversing movement.

The formation of casting bars with a ledge, to form a positioning recess on the

edges of a cast, and to form a guideway along the interior of said cast, and act as end walls of grooves formed in a core, and means for locking the core to the back.

The arrangement of bolster packing strips over a recess so they can pivot into the recess, and out of the way. The arrangement of an expansion chamber within the core and the locating of a stand pipe to pass by the chamber toward the end of the core.

Reference is to be had to the accompanying drawings, in which—

Fig. 1 is a front end view of a preferred form of the invention. The core is turned vertical and in locked position within the vertically disposed back.

Fig. 2 is a side view. The core is shown in a tilted position away from the back resting on the bottom ring and the pouring sheet is shown pivoted over and in alignment with the core, also moved up the guideways.

Fig. 3 is a side view with a portion of the back broken away to show the tilted bottom ring. The core is turned to the horizontal position with a cast which is partly broken away to show the core, and supported on plate rails, above and free from the core's periphery. The front frame is removed and the end frame sectioned about its center, one of the core support extending arms is also removed. The pouring sheet is shown turned up and supported over the pivot rod.

Fig. 4 is a front end view showing the members in the same position as in Fig. 3.

Fig. 5 is a plan view with parts broken away and in the same position as in Fig. 1.

Fig. 6 is a vertical section on line AA of Fig. 5 of the upper end of the mold members and illustrates the core pouring sheet guideway and its co-acting spring actuated latch. The core is presumed to be moving into the back. The end of a core supporting rod is about to be engaged by the latch.

Fig. 7 is a horizontal section of the back sectioned on line B of Fig. 3 and illustrates the sliding matrix positioning fingers engaged with the core operating cams.

Fig. 8 is a horizontal section on line CC of Fig. 1 with the casting bars in the open position and the bolster packing strip tilted back into its recess.

Fig. 9 is the same as Fig. 8 with the casting bars in locked position.

Fig. 10 is an enlarged cross section of the back and core, a cast is shown fast to the core's periphery and a flexible matrix adhering to the cast. This view illustrates the bolster packing strip tilted and pushed back into its recess for the purpose of allowing the cast and matrix to pass by. It also shows a casting bar moved back, and how the bar acts as means for forming a recess along the edge of said cast.

Fig. 11 shows the slide finger, and the core operating cam, in the engaged position, the cam supporting arm is sectioned on line DD of Fig. 7.

Fig. 12 is a horizontal section taken on line EE of Fig. 13 and is particularly intended to illustrate the joining of the bottom ring and casting bars and a bottom ring bolster support.

Fig. 13 is a fragmental illustration showing the back sectioned vertically and centrally as indicated in Fig. 12, the core seated on the bottom ring and its pivot support. A portion of a cast C is shown sectioned as in the back, a portion of a matrix M is shown between the back and cast.

Fig. 14 is a greatly enlarged view to show how the ring is held by a ring support, how the ring is grooved to form a lock up bevel on the lower end of a cast and how it is joined in the center of a rib forming a groove with the core. It also shows how the lower bolster of a curved matrix is clamped and crimped between a bolster supporting ring formed in the back's concavity, and a projection on the top edge of the bottom ring.

Fig. 15 shows a back in section with a matrix bolster B positioned over and in front of the back's bolster support. It also shows the bottom ring in the tilted position just before engaging and crimping the bolster, a fragment of the ring is dotted in to show its normal tilted position.

Fig. 16 is a front view of the bottom ring support with the ring attached.

Fig. 17 is a plan view of the bottom ring shown in Fig. 16.

Fig. 18 is a cross section of the core and its supporting brackets taken on line FF of Fig. 1. It also shows the plate supporting rails in section.

Fig. 19 is a plan view of the casting bars, and their co-acting parts.

Fig. 20 is a vertical cross section on the line 20-20 of Fig. 5 of the core supporting roller and its rail guard.

Fig. 21 is an end view of a plate cast by this machine to illustrate the purpose of forming a recess on the inner straight edge of the cast, and how one side of a plate guide rail of a finishing machine enters so a

shaving knife can pass. It also shows how the shaving knife will remove any fins formed on the plate rib where the ring and core join.

Referring to the drawings, a concave back 10 is made fast in a vertical position between and at one end of a pair of side frames 11 and 12. The top edge of each side frame is formed with a reversed V track 13.

A co-acting convex core 14 is located in front of the back's concavity. The core is mounted on extensions 15 formed on a pair of core supporting brackets 16, and made fast to the extensions by cap screws 17. See Fig. 18. Each supporting bracket has an outward extending arm 18, in which is fastened a short stud 19, on which is rotatably mounted a V faced core carrying roller 20, located on the side frame V tracks.

The ends of the core supporting brackets (toward the back) are formed with a bearing in which is located a core rock shaft 21. See Figs. 3 and 7. Fastened to the center of this rock shaft is one end of a core turning rock lever 22. The opposing end is held by a pin 23, located in bearings formed on a cross end frame 24. This rock lever causes the core to turn as the rollers move along the tracks, toward the back, and the lower end of the core enters in and on a bottom ring 25. See Fig. 2. The bottom ring 25 is mounted on a pivoted ring support 26 operative on short studs 27, located in bearings on the bottom of the back 10. See Figs. 2 and 3.

The bottom ring 25 performs the functions of closing the bottom of the casting chamber, holding the bottom curved side of a flexible matrix, forming a bevel on the lower end of a cast, necessary for "lockup" on the printing press, and one half of the lower rib formed on the concave side of a cast. The ring is recessed on its top edge. The outer side of the recess has a bevel 28 called the "lockup bevel". The opposite side is vertical with a short bevel 29 at the top, called the "rib bevel." This bevel 29 forms (when the core is seated over the ring) one side of a V-shaped recess or groove. See Figs. 14 and 16. By thus uniting the ring and core the joining comes in the center of a rib R, formed on the interior of the cast and any leakage, due to improper seating, is taken care of in the finishing operation, of shaving the cast as shown in Fig. 21.

The ring support is held up in an angular position by a compress spring 94, mounted on a push rod 95, operating thru a recess formed in a cross brace 96.

The outside of the ring is provided with a positioning ledge 30, which engages over a corresponding ledge 31, formed in the back's concavity. See Figs. 14 and 15.

A bolster packing ring 32, let into the back engages the under side of a bolster B, formed on the lower margin of a matrix. See Fig. 15. The bottom ring 25, is provided with a co-acting ledge 33, around its top periphery as shown in Fig. 15. This ledge 33, bending the bolster back or crimping it so it is firmly held between the ring and ledge, making thereby a perfect sealing means, regardless of the variation in the thickness of the matrix. See Fig. 14.

The bottom ring 25 is mounted on and attached to its support 26, so it will have freedom to fluctuate slightly with the changing temperature to conform with the expansion and contraction of the core, caused by intermittent casting. For this purpose there are provided three studs 27 threaded near their heads and blank at their ends. See Figs. 14 and 17. They are threaded from the inside of the ring support 26, and their blank ends are located in corresponding holes in the ring 25.

The means forming the straight side walls of the casting chamber compose two slide bars, called "casting bars" 34. See Figs. 5, 12 and 19. The casting bars are located between the core 14, and the core supporting bracket 16. They are provided with recesses 35, through which pass the core supporting bracket extensions 15, by which the bars are guided. The casting bars are joined together by two pairs of toggle levers 36. The knuckled joint stud 37, of the toggles is made fast in a longitudinal slide bar, 38, operating in guideways formed on the under face of the core. One of the toggle levers is provided with an operating lever 39, by the rocking of which the casting bars are caused to move out beyond the convex edges of the core, or retract within the said edges.

When the core is in casting position, within the back's concavity, the core is locked rigidly in position, by the expanding of the toggles and pushing out of the casting bars until two projecting ledges 40, formed on the bars, engage under a set of locking hooks 41, fast on the edges of the back 10.

Located beneath the locking hooks 41, in a recess formed along the straight edges of the back's concavity, are bolster packing strips 42. Each strip has formed on its inner edge a slight projection 43. This projection extends within the radius of the back's concavity, and is the means for supporting the matrix bolster B along the straight margins of a matrix. See Figs. 10 and 13.

Alongside of, and parallel with, each locking extension 40 of the casting bars is an elevation 44 which engages in front of a matrix bolster B and clamps it against the projection 43 of the bolster packing strip. The top of this elevation 47^a forms part of the side wall of the casting chamber. The

longitudinal bolster packing strip 42 is centrally located over an incline forming a recess 45, back of this incline is a vertical wall 48^a against which the bolster packing strip engages and is held against the advanced casting bar. The bolster packing strips 42, are held loosely in position by two pivot pins 46.

On unlocking the core from the back with a cast adhering to the core's periphery, the bolster packing strip is rocked forward and pushed back into the recess 45, by the advance of the matrix bolster B, and cast C, as plainly shown in Fig. 10.

A recess 47, formed along the edge of each casting bar 40, and located next the core forms a ledge 48 extending into the casting chamber for the purpose of forming a corresponding recess S, in a cast C, said recess acting as a means for positioning a cast in a finishing mechanism, (not shown) see Figs. 3 and 19.

This longitudinal recess 47, forms an extension to the casting chamber beyond the circumference of the core, and due to the recess being of a less depth than the thickness of the cast, its rear wall is in advance of the periphery of the core, and forms a corresponding longitudinal recess G along the interior edge of the cast, and permits of one side of a guideway J of a finishing mechanism entering so a shaving knife K can pass, as shown in Fig. 21. See Figs. 10 and 19.

V-shaped grooves are formed entirely around the core's periphery to form corresponding ribs R, on a cast. The ends of the grooves are closed by the side faces of the casting bars, whereby the ribs formed on the cast are made shorter than the periphery of said cast.

On the upper end of the back is a thin metal pouring sheet, curved to fit the concavity of the back. The purpose of the pouring sheet is to overlap the top edge of a flexible matrix and guide the molten metal past and over the top edge of said matrix, when placed in casting position, within the back's concavity. The pouring sheet is arranged so it can be instantly positioned within the back for casting purposes, and thereafter follow the cast out of the back, move lengthwise of the cast to withdraw from engagement with the matrix, separate from the cast, and move to a support over the back's concavity. See Figs. 2, 3, 4 and 5.

The means I employ to procure this result comprises a pair of vertically disposed brackets 49, made fast, one at each side of the back's concavity. The upper ends of the brackets are connected by a tie rod 50. In front of the tie rod is located a rock shaft 51, upon which are made fast two rock arms 52. In bearings formed on the

free ends of the rock arms are located pouring sheet pivot rods 53. Each rod is formed with a square edged collar 54, located to engage the inner face of the rock 5 arm bearings. The pouring sheet 55 has straight parallel backward extending wings 56, provided with a hole, through which pass the inner rod ends 53. A lock nut is located on the rod for the purpose of clamping the 10 wing 56 against the collar. The outer end of the wing 56 is turned outward to engage against one of the straight faces of the collar 54, for the purpose of preventing its possible turning on the road.

15 Located on the pivot shaft is an eccentric mechanism, consisting of an eccentrically mounted wheel 58, on which is mounted a ring 59. This ring is provided with an outwardly extending bearing in which is pivot- 20 ed one end of a pull spring 60, the opposite end of which is held by a small bracket 61, fastened on top of the back. See Fig. 6.

Made fast to the upper end of the core 14 is a pair of brackets 62. Each bracket 25 has a vertically disposed guideway 63. A gap is formed through the guideway at its bottom, in which is located a spring actuated latch pin 64. See Fig. 6. The purpose of this latch is to allow the inner ends 30 of the pouring sheet rods 53, to pass through the gap by pushing down the latch as the core moves vertically and take up a position in front of the latch pin and in alignment with the guideway. See Figs. 6 and 1. In 35 this position the pouring sheet rods 53, are caused to follow the guideways 63, during the rocking of the core out of the back. As this rocking progresses the rods 53 are caused to move up along the guideways by 40 their pivoted arms 52 until the guideway passes under the rods. During this operation the pouring sheet 55 has followed and pulled lengthwise of the core, and out of the matrix engaging position. See Fig. 2. 45 As the rods 53, become free from the guideways, the eccentric comes into play and the spring tension causes the eccentric to act as a lever and pivot the pouring sheet on its support on top of the pivot shaft and stay rod to 50 the position shown in Figs. 3 and 4.

For the purpose of holding and positioning a matrix in curved position within the back's concavity, when the core is out of casting position, I have arranged automatic 55 operating slide fingers 65 along the straight sides of the back. The slide fingers 65 are mounted on angle brackets 66, which are fastened on the straight side of the back 10. The fingers are slidably mounted in dove-tailed guides in the angle brackets, Fig. 3. They are located so their inner sides can be 60 pushed over and engage the top side of the bolster packing strip 42, and cause it to pivot over from the tilted position shown in Fig. 10 on to the flat edge of the back, and

in the position shown in Fig. 7, and then pass over the edge of the bolster packing strip into the concavity of the back, as in Fig. 7.

In this position, a matrix is curved so its straight sides engage beneath the slide fingers and then the matrix is pushed down until its bottom curved end rests upon the ledge 31, formed in the bottom end of the back's concavity, and its curved bolster B 75 envelopes the bolster support ring 32, whereupon it is in casting position. The pouring sheet is then pivoted down over and on to the top margin of the matrix by the pouring sheet operating handle 67. The core is then rolled forward and turned over by lifting up and pulling forward on the lever 39 until a seat 68 formed on the end of the supporting brackets 16 engage supporting seat 69 formed on the bottom ring support 26, and the core comes to rest on top of the bottom ring (see Fig. 2). The core is then pivoted over on the ring pivots until it is stopped by positioning lugs 70, formed on the core supporting brackets near the top. Then the lever 39 is pushed up as in Fig. 1, which causes the toggles to expand and push the casting bars out, whereupon the advanced side of the locking projection 40 95 will engage the inner side of the fingers 65, and push them back as shown in Fig. 9.

On moving the core back to its horizontal position, cam plates 71 fastened to each lower face of the core supporting brackets, engage a projecting arm 72, on the slide fingers and cause the fingers to move in as shown in Figs. 7 and 11.

When the core with a cast formed thereon is moved out of the back it is necessary to remove the cast from the periphery of the core. For this purpose I have located a plate carrying rail 73 at each straight side of the core, and arranged them so they would hold the cast in parallel alignment with the face of the core. For this purpose the plate supporting rails 73 are made movable in a vertical plane toward and over the sides of the core. The rail is formed with an inward extension 74 (see Fig. 1) located in a groove formed at right angles to the core in the side of the core supporting bracket. The rail is held in position by a stud 75. See Fig. 18.

As the core is turned toward the horizontal position, a foot 76, formed on and beneath the rail 73, engages a cross brace 77, and as the core turning movement continues the brace holds the rails, and the core continues the turning movement to a horizontal position, during which the guideways move down along the projection 74 on the rail. This causes the rail's top edge to engage the straight sides of a cast located on the core and holds it against the downward advancing motion of the core. This

motion causes the cast to separate from the core and rest on the rails as shown in Figs. 3 and 4.

On the reverse motion of the core the rails are forced back by lugs 78, formed on the outside face of the rails, engaging against stops 79 formed on the central locking hooks 41. See Figs. 4 and 5.

For the purpose of clearing the rail 13, over which the core supporting roller 20 operates, I have arranged a guard to travel along and with the roller. The guard 80 is located in a groove formed in the face of the roller 20, and slides along and in advance of the roller, in either direction. See Figs. 5 and 20.

The back is provided with an inlet pipe 90, at its bottom for the passage of cooling water into a chamber W. For the purpose of keeping the chamber completely filled with water at all times, there is a stand pipe 91, entering through the bottom and extending to a short distance from the top. See Figs. 2 and 6.

25 A cooling chamber X is provided in the core. This chamber is formed with a distributing pocket Y at its bottom into which water enters through an opening 92, Fig. 8. Near the top is an expansion chamber Z for the purpose of overcoming the danger of the inner wall being pulled apart by the longitudinal expansion of the outer casting surface, and is means for equalizing the expansion. An overflow pipe 93, is located so as to extend through the expansion chamber to the end of the cooling chamber. This pipe is to prevent the formation of steam or collection of air above the expansion chamber or in the top of the cooling chamber when in casting position. See Fig. 6.

Having described the construction of my invention, I will now explain its operation.

The core is placed in the horizontal position, with the pouring sheet on its support as shown in Fig. 3. A flexible matrix M is then curved with its casting face within. The two lower corners of the matrix bolsters B are inserted beneath the inner ends of slide fingers 65. The matrix is then pushed backward on the concave face of the back, and down until its lower curved edge engages the back's positioning ledges. The pouring sheet 55 is then turned down. In this position the lower end of the pouring sheet will overlap the top edge of the matrix. Having positioned the matrix in the back, the core is rolled forward until its bottom engages with the bottom ring 25 as shown in Fig. 2. From this position the core rollers are lifted slightly from the tracks and the core is pivoted with the bottom ring into casting position within the back, in which position it is stopped by the positioning stops 70.

65 The operator now lifts straight up on

the core turning handle 39, which lifting causes the casting bars to move out from beneath the core and engage the inner ends of the matrix positioning fingers 65, pushes them out and the projections on the casting bars beneath the locking hooks, thereby locking the core and back in position to receive a charge of molten metal through the chamber's open top.

After allowing time for the metal to solidify, the operator pulls down on the handle 39 and unlocks the chamber. He then pulls back and pivots the core away from the back, carrying the cast and matrix along. During this pivotal movement the pouring sheet is caused to follow the core, and owing to its independent pivoted movement, it moves transversely away from the matrix. The core begins to lift out of the bottom ring and turn. The pouring sheet supporting rods move along the core guideways until the guides pass under, whereupon the eccentric 58 continues the pouring sheet pivot movement and carries it to its support as in Fig. 3.

The lower ends of the core plate rails engage with their stop, and the cast is transferred from the core to the plate rails as shown in Figs. 3 and 4. Simultaneously with this engagement the fingers 65 are shoved back into the matrix holding position by the cam plates 71, Fig. 7.

The operator then peels the matrix free from the cast and re-positions it for a following operation. The cast is then slid along the rails into a finishing mechanism, or any other support, to be located in front.

Having now particularly described and ascertained the nature of my invention, and in what manner the same is to be performed, I declare that what I claim is:

1. In a curved stereotype plate casting apparatus, the combination with a back supported in fixed position, and a core movable in front of the back, of fingers mounted on the back for engaging and holding a matrix against the core, and automatic means for sliding said fingers in and out as the core moves.

2. In a stereotype plate casting apparatus having a back and core, the combination with matrix positioning means on the back, of means on the core for moving the matrix positioning means in for the purpose set forth.

3. In a casting apparatus, a casting back provided with means for positioning a matrix slidable inwardly toward the core in a straight line, and independent means for moving the positioning means into or out of engaging position.

4. In a curved stereotype casting apparatus having a back supported in a vertical plane and core supporting tracks, between which said back is located, the com-

- bination of a core operative on said tracks, a slide finger located on each side of the back, of means carried with the core for moving the finger in when the core is 5 moved away from the back to clamp the matrix to the core, and out of the way when the core is moved to the back.
5. In a curved stereotype casting apparatus, the combination with a concave back, 10 of positioning means located at each straight edge of the concave back, and means for automatically moving the positioning means into and out of operative position, for the purpose set forth.
- 15 6. In a stereotype plate casting apparatus having a back and core, the combination with matrix positioning means on the back, of means on the core for moving the matrix positioning means in, said means comprising cam plates projecting beyond 20 the core, said matrix positioning means having arms located in position to be moved by the cam plates as the core moves in or out.
7. In a curved stereotype plate casting 25 apparatus, the combination with a curved casting box adapted to support a matrix, of a bolster packing ring in position to engage the convex side of the matrix bolster, with means on the concave side for holding the top of the bolster of the matrix and crimping it against the bolster packing ring.
8. In a curved casting apparatus, the 30 combination of a bottom ring, a support therefor, of means for holding the said ring so it can change its curvature with changes in temperature for the purpose set forth.
9. A curved casting apparatus, having a bottom ring formed with a groove around 40 its top face having two inclined surfaces, for the purpose set forth.
10. In a curved stereotype casting apparatus, having a segmental core and a co-acting back, the combination with a ring 45 support pivoted beneath the casting apparatus, of core seating means located over and extending beyond each side of the pivot, for the purpose set forth.
11. A curved stereotype casting apparatus having a convex core and a bottom ring, grooves being formed around the periphery of said core, one side of a groove formed near the bottom of said core, and a co-acting side of a groove formed on the 55 aforesaid ring, for the purpose set forth.
12. In a curved stereotype casting apparatus, the combination with a vertically disposed concaved back, and a bottom ring pivotally held in the back's concavity, of 60 a compress spring for supporting the said ring in a tilted position for the purpose set forth.
13. In a curved stereotype casting apparatus, the combination of a matrix bolster 65 supporting means located to support the convex side of a bolster formed on a flexible matrix curved and positioned within the back's concavity, a movable bottom ring located within the back's concavity and facing the aforesaid bolster supporting means 70 having a projecting top edge formed on the outside face of the ring, and means for moving the ring so the projecting edge engages the convex face of a bolster formed in said matrix at the upper side of the bolster 75 supporting means, for the purpose set forth.
14. A casting apparatus having a vertically disposed back upon which is pivotally supported a pouring sheet that can be swung on its pivot into or out of engagement with the back, for the purpose set forth.
15. In a casting apparatus, a back and a core, means for supporting a pouring sheet, means for moving the pouring sheet into casting position, and movable means for moving the said pouring sheet out of casting position automatically for the purpose set forth.
16. In a casting apparatus, a vertically disposed back and a core, means on the back 90 for supporting a pouring sheet, means for moving the pouring sheet into casting position, and movable means on both the core and back for moving the said pouring sheet out of casting position automatically for the 95 purpose set forth.
17. In a curved casting apparatus having a vertically disposed back, a pouring sheet, pivoted arms located above the back for supporting the pouring sheet, and means whereby the pouring sheet can be swung down into the back's concavity, for the purpose set forth.
18. In a casting apparatus having a casting back, a pouring sheet, pivot arms for supporting the pouring sheet, so located that the pouring sheet can be turned down and engage the casting face of the said back, and means for assisting said sheet to reverse the pivotal movement for the purpose set forth.
19. In a curved stereotype casting apparatus, having a back and a movable core, the combination of a pouring sheet supported above the back, pivotal means for moving the pouring sheet to engage the back, and means on the core for moving the said pouring sheet out of engagement with the said back, for the purpose set forth.
20. In a casting apparatus having a fixed back and a pivoted core, a sheet over the back, a pivot arm fast on said shaft, a pouring sheet carried by said arm, means for supporting the pouring sheet above the said shaft, means on the core for moving the pouring sheet in alignment with the pivotal movement of the core and simultaneously lengthwise of said core, and means for thereafter causing it to swing up to its support.
21. In a casting apparatus having a verti-

cally disposed fixed back and a pivoted core, a bracket, a shaft over the back, supported by the bracket, a pivot arm fast on said shaft, a pouring sheet carried by said arm,

5 means for supporting the pouring sheet above the said shaft, means for swinging the said pouring sheet down on the back, means on the core for moving the pouring sheet in alignment with the pivotal movement of the core and simultaneously length-

10 wise of said core, and means for thereafter causing it to swing up to its support.

22. In a curved casting apparatus, a curved pouring sheet having extending wings provided with a recess and a ledge at their ends, a supporting rod formed with a straight side edge, one end of said rod extending through the recess and the straight side engaging the aforesaid ledge, and means 15 for holding the pouring sheet and rod in locked position for the purpose set forth.

23. A curved stereotype casting apparatus having a curved pouring sheet formed with a pair of parallel projecting wings, and 20 pivot rods secured to said wings.

24. In a curved stereotype casting apparatus, the combination of a vertically disposed concaved back, a pouring sheet curved to fit the back's concavity, means for moving the said pouring sheet out of engagement with the back's concavity, and means 25 for thereafter swinging it upward and over the moving means, for the purpose set forth.

25. In a stereotype plate casting apparatus having a movable core, the combination therewith of guide-ways located on the end of the core, a back co-operating with the core, a pouring sheet movably mounted on the back, and a latch on the back co-40 operating with the guide-ways, for the purpose of controlling the motion of the pouring sheet.

26. In a casting apparatus, the combination of a vertically disposed concaved back, side frames having tracks thereon, a segmental convex core located between the frames, a supporting bracket attached to each side of the core, a projecting arm on each bracket on the outer end of which is mounted a roller, located above and on said track, and means for swinging the core as the rollers move along the tracks for the purpose set forth.

27. In a casting apparatus, a concave back having a convex segmental core of a circumference less than the back and provided with grooves formed around the periphery, means for spacing the core and back to form a curved casting chamber therein between, and 50 movable means for closing the groove end opening, and extending the core side of the chamber to correspond with the back's circumference, as and for the purpose set forth.

28. In a casting apparatus having a curved casting chamber formed between a

segmental back and core, the combination therewith of bars slidably operative over the core edges to form the side walls of the chamber, and means on the bars for forming a portion of the chamber of a less circumference than the main chamber for the purpose set forth.

29. In a curved stereotype casting apparatus having a segmental core, the combination of core supporting brackets formed with elevations to which the core is fixed, slide bars located between the core and brackets and operative alongside the aforesaid elevations, toggles for moving the bars, and means for operating the toggles for the purpose set forth.

30. In a curved stereotype casting apparatus having a movable segmental core, supports solidly attached to each straight side of the core and having grooves formed in the outer faces thereof at right angles to the flat face of the core, cast carrying rails operative in the grooves, and means for moving the rails along said grooves for the purpose set forth.

31. In a casting apparatus, having a convex segmental core, the combination of supports fastened on each side of the core, a cast supporting rail operative on each core support, and means for holding the said cast supporting rails parallel with the periphery of the core at all times.

32. In a casting apparatus having a concave back and convex core, supports for the core, supporting rails operative on the core supports, means for holding the said rails in alignment with the periphery of the core, means for moving the core and its supports, means for stopping the rail during a portion of the movement for the purpose of 105 engaging the edges of a curved cast and holding said cast against further movement of the core for the purpose set forth.

33. In a casting apparatus having a concave back and convex core, supports for the core, matrix clamping means carried by the core, cast supporting rails operative on the core supports, means for holding the said rails in alignment with the periphery of the core, means for moving the core and its supports, and means for stopping the cast supporting rail during a portion of the movement for the purpose of engaging the edges of a curved cast, located on the periphery of the core and holding said cast against 120 further movement of the core, and means for stopping and holding the rails to reverse the movement for the purpose set forth.

34. In a casting apparatus having a vertically disposed concave back, a segmental convex core cooperating with the back to form a curved casting chamber therein, movable members on each straight side of the segmental core for forming the side walls

of the casting chamber, a toggle mechanism connecting the movable members, a slide bar connected with the toggle and operative in fixed bearings, and means for moving the 5 slide bar to expand or contract the toggle arms for the purpose set forth.

35. In a curved stereotype casting apparatus, a vertically positioned back, a core movable from a horizontal position in front 10 of the back to a vertical position within the back, means carried with the core for separating a cast from the casting face of the core, and means on the back for repositioning the separating means, for the purpose 15 set forth.

36. A casting apparatus having a fixed mold member, a movable mold member, a track, and a roller operating along the track, said roller having a recess formed about its 20 periphery in which is located a guard caused to slide along and keep the said track clear for the purpose set forth.

37. A segmental core having a water cooling chamber, the inner wall of which is 25 formed with angles for the purpose of equalizing the expansion of the casting face of said core.

38. A segmental core provided with a cooling chamber, and a distributing chamber 30 located at one end and an expansion chamber near the opposite end.

39. A segmental core having a cooling chamber and an expansion chamber, and a stand pipe passing through and above said 35 chamber, for the purpose set forth.

40. In a stereotype plate mold, the combination with a back and core, of a movable packing strip at the edge of the back having means for engaging the back of the 40 edge of a matrix at the margin thereof, and a positioning finger outside the mold movable inwardly toward the mold cavity for engaging said packing strip and moving it into place.

45. 41. In a stereotype plate mold, the combination with a back and core, of a movable packing strip at the edge of the back, a positioning finger outside the mold mounted to slide inwardly toward the mold at an 50 angle and having a point for engaging the packing strip, and means for guiding and supporting the finger.

42. A stereotype plate casting box having 55 longitudinal bolster packing strips movable to a transverse position across the edges of the mold cavity to support the matrix bolsters along the straight margins of the matrix and capable of rocking to free the matrix bolsters.

60 43. A stereotype plate casting box having 65 longitudinal triangular spaces in the edges of the back, and bolster packing strips swingingly mounted on the edges of the casting box and capable of being moved to a transverse position in the mold to sup-

port the matrix bolster along the straight margins of the matrix and capable of moving into said triangular spaces when withdrawn from engagement with the matrix bolster.

70 44. In a stereotype plate mold, the combination with a back and core, of a movable packing strip at the edge of the back provided with an inwardly extending lip at its edge for engaging behind the edge of the matrix and a matrix clamp adapted to be moved outwardly from within for engaging the edge of the matrix over said lip and clamping it thereto.

75 45. In a stereotype plate mold, the combination with a back and core, of matrix clamps carried by the core, and means for turning the core into the concavity of the back and for thereafter moving the matrix clamps into position in the back to form the straight side walls of the casting chamber.

80 46. In a stereotype plate mold, the combination with a back and core, of matrix clamps and locking bars on the core, slideways on said bars, slides movable along 85 said slideways, rocking levers connecting the said slides for operating them, and means for rocking said levers for the purpose set forth.

85 47. A stereotype plate casting box having a semi-cylindrical core and back and a casting bar on each flat edge of the core, said bars each having a longitudinal recess providing an extension of the casting chamber beyond the periphery of the core for producing longitudinal recesses along the interior edges of the cast plate for receiving a finishing machine guide-way.

90 48. In a stereotype plate mold, the combination with a back and pivoted core, of a pouring sheet pivotally mounted on the back, means on the core for moving the pouring sheet in alignment with the pivotal movement of the core and simultaneously lengthwise of the core, and means for thereafter causing the sheet to swing up on its support.

95 49. In a stereotype plate mold, the combination with a back and pivoted core, of a pouring sheet pivotally mounted on the back, means on the core for moving the pouring sheet in accordance with the pivotal movement of the core, the pouring sheet having extending wings each provided with a recess and a latch at its end, a supporting rod formed with a straight side edge, one end of said rod extending through the recess in one of the wings and a straight side 100 engaging said latch, and means for holding the pouring sheet and rod in locked position.

105 50. In a stereotype plate mold, the combination with a back and pivoted core, of a pouring sheet pivotally mounted on the back, a pivotal supporting device for the 110

pouring sheet, an eccentric thereon, an eccentric ring on the eccentric connected with the pouring sheet to move therewith, yielding means for holding the eccentric ring in position to hold the pouring sheet up away from the mold, and means on the core for turning the eccentric as the core swings out of the back.

5 51. In a stereotype plate casing box, the combination with a casting back and a core therefor having circumferential grooves for

casting parallel ribs on the plate and provided with an end recess extending from the end groove to the end of the core, of an end ring extending into said recess and 15 having an end surface for casting part of said end rib, whereby the joint between the core and end ring comes at the rib.

In testimony whereof I have hereunto affixed my signature.

CHARLES E. HOPKINS.
